[57] CLAIM

The ornamental design for a socket drive tool, as shown and described.

DESCRIPTION

FIG. 1 is a perspective view of a socket drive tool showing my new design;

FIG. 2 is a right side elevational view with the left side being a mirror image thereof;

FIG. 3 is a top view thereof;

FIG. 4 is a bottom view thereof; and,

FIG. 5 is a front elevational view, the rear elevational view being a mirror image thereof.

The broken line showing of the user's hand, the socket, the bolt and the article from which the bolt is protruding in FIG. 1 is for illustrative purposes only and forms no part of the claimed design.
